UNITED STATES PATENT OFFICE.

HENRY ALLEN, OF SILVERTON, OREGON.

APPARATUS FOR OPERATING ROLLER-GATES.

SPECIFICATION forming part of Letters Patent No. 224,121, dated February 3, 1880.

Application filed October 11, 1879.

To all whom it may concern:

Be it known that I, HENRY ALLEN, of Silverton, in the county of Marion and State of Oregon, have invented a new and Improved 5 Apparatus for Operating Roller-Gates, of which the following is a specification.

Figure 1 is a perspective view of my improvement attached to a double-roller gate. Fig. 2 is a side elevation of the gate. Fig. 3 10 is a detail section taken through the line *x x*, Fig. 2. Fig. 4 is a detailed view of the device for operating the latch.

The object of this invention is to furnish an 15 improved apparatus for attachment to roller-gates, the use of which will enable a person in a vehicle or upon horseback to open and close the gate.

The invention consists in providing a roller-gate with an endless chain or rope and a series of pulleys so arranged that the movement 20 of the said chain or rope in one direction will open the gate and its movement in the other direction will close the gate.

A and B are two pairs of posts, set at the 25 opposite sides of the roadway and at such a distance apart that the parts C D of the gate may pass between them. E F are posts set at such a distance from the posts A B as to serve as stops to the parts C D of the gate 30 when opened.

To one post of each pair A B is attached a cross-bar, G, the ends of which are attached to the posts E F. The upper edge of the cross-bar G is rounded or beveled to receive the grooved rollers H, which are pivoted to arms I, attached to the corners of the parts C D of the gate, and which carry the gate as it is opened and closed. The upper ends of the posts A B E F are connected by a cross-bar, J, 35 which is made wide, to serve as a cap to protect the operating parts of the mechanism. The lower part of the gate is kept from lateral movement by being placed between the adjacent edges of two bridge-planks secured to bed-pieces set in the roadway. At one side of the roadway, and at a suitable distance from the posts A, are set two posts, K. To the inner sides of the upper parts of the posts K are attached pulleys L, around which passes an end- 40 less chain or rope, M.

The chain or rope M, in passing between the pulleys L, passes over a pulley, N, pivoted to the cap-bar J. The other part of the chain or rope M, in passing from the pulleys L, passes around two pulleys, O, pivoted to the posts A, 55 and around a single pulley, P, pivoted to the posts B. The two parts of the chain or rope M that cross the roadway are connected with the arms I, attached to the inner corners of the parts C D of the gate, so that the said 60 parts C D may be drawn toward each other when the chain or rope M is drawn in one direction, and from each other when the said chain or rope is drawn in the other direction.

The chain or rope M is connected with the 65 arm I' of one of the parts C D of the gate by a long loop or keeper, Q, attached to the said chain or rope, and through which the end of the said arm passes, so that the rope or chain may move a little distance before it moves the 70 said part of the gate. To the upper end of the arm I' is attached a pin, X', or other stop, to prevent the loop Q from being drawn from the said arm I' when power is applied to the 75 rope or chain M. The chain or rope M is connected with the other part of the gate by the three-armed lever R, which is pivoted to the arm I''. The upper arm of the lever R is fastened to the rope or chain M. To the lower arm of the lever R is attached the upper end 80 of a rod, S, the lower end of which is attached to the gate-latch T, so that the said latch may be raised from its catch U by the movement of the said lever R. The movement of the lever 85 R is limited by a pin, V, attached to the arm I'', and which passes through a slot, W, in the said lever R, as shown in Fig. 4.

With this construction the loop Q and the slot W allow the rope M to move a sufficient 90 distance to raise the latch T before the said rope M acts upon the parts C D of the gate.

To the chain or rope M, upon the opposite sides of the gate, are attached handles X, of rope, wood, or other suitable material, for convenience in operating the said rope to open 95 and close the gate.

I have described my invention as applied to a double-roller gate; but it is equally applicable to a single-roller gate.

Having thus described my invention, what 100

I claim as new, and desire to secure by Letters Patent, is—

1. The combination of the loop Q, the slotted lever R, rod S, and latch T with endless chain or rope M and gate C D, substantially as herein shown and described, so that the chain or rope M may move sufficiently to raise the latch T before the gate is acted upon, as set forth.

2. The combination of the arm I' and loop Q with the gate C and rope or chain M, substantially as herein shown and described.

HENRY ALLEN.
